Patented July 16, 1912.

UNITED STATES PATENT OFFICE.

ELDON H. SHAVER, OF ORENCO, OREGON.

RAZOR-STROP.

1,032,954.

Specification of Letters Patent. Patented July 16, 1912.

Application filed October 31, 1911. Serial No. 657,732.

To all whom it may concern:

Be it known that I, ELDON H. SHAVER, a citizen of the United States, residing at Orenco, in the county of Washington and State of Oregon, have invented certain new and useful Improvements in Razor-Strops, of which the following is a specification, reference being had therein to the accompanying drawing.

10 This invention relates to receptacles for razors, and the principal object of the same is to provide a receptacle having a smaller receptacle mounted therein in which the razor is carried and to provide the outer receptacle with a covering of leather or some other similar material so that the razor may be stropped upon the receptacle, the inner receptacle being drawn out part way to form a handle.

15 The invention is illustrated in the accompanying drawings, wherein:

Figure 1 is a perspective view showing the device in position to be used as a razor strop. Fig. 2 is a view of the receptacle closed. Fig. 3 is a section along the line 3—3, Fig. 2.

Referring to the accompanying drawings by numerals it will be seen that this invention comprises an outer receptacle 10 which is preferably formed of tin or some other rigid material and which is provided with a covering 11 of leather. A packing 12 is positioned between the receptacle 10 and the covering 11 so that the strop will be softer than would be the case if the leather were mounted directly upon the tin receptacle. The outer edges of the receptacle are provided with recesses 13 in opposite sides so that the inner receptacle may be drawn out easily when desired. A cover 14 is hinged to the outer receptacle 13 and fits over the edges of the outer receptacle when closed so that the razor will be held in the box. The razor is kept in an inner receptacle 15 which fits in the outer receptacle and is provided

with recesses 16 so that the razor may be easily withdrawn and is also provided with projections 17 upon the opposite sides which fit into the recesses 13. These projections 17 afford easy means for withdrawing the inner 50 receptacle from the outer receptacle and also hold the cover closed, the side flanges of the cover frictionally engaging the projections 17.

When using this device the cover is moved 55 to the position shown in Fig. 1 and the projection 17 grasped and the inner receptacle drawn out as much as desired so that it will form a convenient handle. The razor is then withdrawn from the inner receptacle 60 and can be stropped upon the leather covering of the outer receptacle. It will thus be seen that this device not only forms a receptacle for containing the razor but is also used as a razor strop.

What is claimed is:—

1. A device of the character described comprising an outer casing, the opposite edges of the outer end of said casing being provided with cut-out portions, an inner 70 casing fitting in said outer casing, lugs formed upon said inner casing and fitting into the cut out portions of said outer casing, and a closure for said outer casing held in a closed position by frictional engagement with said lugs.

2. A device of the character described comprising an outer casing, a cover hinged to said outer casing, an inner casing fitting within said outer casing, and common 80 means carried by said inner casing for facilitating the withdrawal of said inner casing and for holding said cover in a closed position.

In testimony whereof I hereunto affix my 85 signature in presence of two witnesses.

ELDON H. SHAVER.
